ELECTROMAGNETIC COUPLING DEVICE

Loya Bryan Perkins, Lufkin, Tex.

Application February 21, 1945, Serial No. 579,030

3 Claims. (Cl. 175—359)

1

This invention appertains to inductance coil or transformer construction, particularly of the air core type for use in radio receiver and transmitter circuits, especially for first detector coupling, although adapted to be used for many other purposes, e. g., for interstage coupling when provided with an iron core.

One of the several objects of the invention is to provide a self-supporting inductance couple, such as a radio frequency transformer, in which the two windings are formed, with or without the use of any of the usual foundation forms and with or without iron cores, and one of the windings is wound upon the other, or so wound in continuation with the other, in a manner to obtain the closest possible coupling and, at the same time, to eliminate a large percentage of the loss, due to leakage of the coils and material capacity, common to many of the coil forms present in the prior art.

Another object of the invention has to do with the provision of a novel and highly efficient form of fixed inductance couple, or transformer, which involves a foundation coil, that is preferably bank wound to a selected diameter and circumferentially indented to form a selected number of radially extending projections or prongs, and a second, or cover, coil that is first wound to the form of a flat spiral and thereafter woven onto the projections or prongs, somewhat after the method involved in the forming of the diamond weave spiderweb coil.

With these and other objects in view, the invention resides in the certain new and useful combination, construction, and arrangement of coils, as will be hereinafter more fully described, set forth in the appended claims, and illustrated in the accompanying drawing, in which:

Figure 1 is a top plan view of the inductance couple or transformer, in accordance with the invention;

Figure 2 is a cross section through two adjacent projections or prongs of the foundation coil, showing the diamond weave of the cover coil thereon;

Figure 3 is a cross section taken through the line 2—3 on Figure 2, showing the close winding of a layer of turns or convolutions of the cover coil;

Figure 4 is a cross section taken diametrically through the cover coil, prior to its assembly on the foundation coil;

Figure 5 is an enlarged perspective detail of one of the projections or prongs of the foundation coil, and showing the interweaving therewith of

2

two adjacent turns or convolutions of the cover coil; and

Figure 6 is a view similar to that of Figure 2, but showing a circular weaving of the cover coil turns or convolutions about two adjacent projections or prongs of the foundation coil.

Referring to the drawing, wherein like characters of reference denote corresponding parts in the several views, the preferred embodiment of the invention, as it is exemplified in Figures 1 through 5, is comprised in a foundation coil 10, constituting the primary winding of the inductance couple or transformer, which is first wound to the form of a plain cylindrical coil having several layers of turns or convolutions one over the other, three of such layers being shown for the purposes of the present description. If the coil is formed as a plain layer winding, instead of being bank wound, there would be a considerable capacity effect, since the first and last turns would come together. Hence, to avoid this excessive distributed capacity, the bank type winding is much to be preferred, although for certain purposes, the plain layer winding may be resorted to.

Upon the completion of the cylindrical coil foundation, it is circumferentially indented to provide a selected number of equidistantly spaced, radially extending, projections or prongs 12, thirteen of the same being shown in Figure 1 of the drawing, and, thereafter, a cover coil 18, constituting the secondary winding of the inductance couple or transformer, is applied to the projections or prongs, preferably, by a method somewhat similar to that employed in the formation of a diamond weave spider web coil. In the forming of the cover coil 18, it is first wound to the shape of a flat spiral and thereafter its several turns or convolutions are woven onto the projections or prongs 12, in the stated manner. By thus weaving the cover coil 18, it retains all of the advantages of a flat spiral winding, while doing away with the disadvantages thereof. In Figure 1, the terminal ends of the foundation coil 10 are indicated at 14 and 16, and those of the cover coil 18, at 20 and 22.

The coil assembly, thus provided, may be employed as an air core inductance couple or transformer, or it may be provided with an iron core (not shown), either solid or laminated, as desired. In the latter case, the core may take the form of a disc, or a disc assembly if laminated, having projections or prongs fitting into the projections or prongs 12, of the foundation coil 10.

For radio receiver antenna coupling, I prefer to have the foundation coil 10 made up of eighteen (18) turns on a four (4") inch diameter, the terminals 14 and 16 connecting the antenna and ground, while the cover coil 18 of half that number of turns and reversely wound, with its terminals 20 and 22 connecting ground to "B—." However, the cover coil 18 may be wound in the same direction as is the foundation coil 10, with equally good results, using the same terminal hookup. In designing the inductance couple or transformer for this purpose, it will be understood that the range of reception of broadcast signals will vary with the number of projections or prongs 12 provided on the foundation coil 10, i. e., the fewer the projections or prongs, the lesser the number of stations to be brought in.

For interstage and like coupling, I make the foundation coil 10 up with twenty-four (24) turns on a three and one-half (3½") inch diameter, while the cover coil 18 may be made up of any lesser of turns, depending upon the "B" of plate voltage. When the foundation coil 10 is initially wound to cylindrical form, the plate reading should be zero, and when indented to form the projections or prongs 12, a plate gain of approximately one-half is obtained. Likewise, upon the completion of the cover coil 18, the plate reading should also read zero, or nearly so. If the inductance value of the cover coil 18 is made to match that of the foundation coil 10, the transformer functions to pass any frequency within its band. However, it is also to be understood that, depending upon the intended use of a couple or transformer, the cover coil 18 can be proportioned relatively to the foundation coil 10, i. e., from less than half length to an over length. In any case, the magnetic field of the foundation coil 10 is compressed, while that of the cover coil 18 is spread, the relationship of the two fields being that of rotation with the current impulse or movement within them, unless the reverse condition is required for a particular circuit arrangement.

In Figure 6, a modified method of associating the cover coil 18' with the foundation coil 10' is illustrated and, here, each turn, or convolution, of the cover coil is looped about each of the projections or prongs 12' of the foundation coil. By making these loops 18" to circular form, they are to be engaged over the projections or prongs 12' with a facility substantially equal to that of the interweaving of the turns or convolutions, as in the first instance.

In the design of these inductive couplings, or transformers, it is to be understood that the depth of the indentations, for forming the projections or prongs 12, 12' in the foundation coil 10, will determine the angular torque of the two coil relationship, i. e., of the magnetic fields thereof, and, also, effect the direction of wind. With the coils 10 and 18 meshing as shown, the angle of approach of the two fields is variable and the degree of that angle determines the electronic angular collision of the fields, which can be headon, or sidewise, i. e., parallel; a compound torque effect being involved in either or both. With the use of a crystal detector, the two coils must be matched by touch units, i. e., self-inductance units.

From the foregoing description of my inven-

tion, it will be evident to those skilled in the radio art that these forms of inductance couples, or transformers, makes for the highest value of mutual inductance, by reason of the closeness of association of the cover coils 18, 18', with the foundation coils 10, 10', and, also, the coincidence of their axes, which value, however, is subject to variation by changes in sizes, diameters, and length, of the two coils, as is well understood.

Having thus fully described my invention, it is to be understood that the disclosed coils constructions are subject to any and all modification that may fall within the scope of the appended claims.

I claim:

1. In a transformer, a first winding comprising a circular turn of wire wound substantially in a plane with radially extending convolutions therein, each convolution comprising an outwardly extending portion and an inwardly returning portion of the wire, and a second winding electrically insulated from the first winding and electromagnetically coupled thereto comprising a further wire wound substantially in the form of a flat helix and extending alternately over and under both portions of each successive convolution.

2. In a transformer, a first winding comprising a circular turn of wire wound substantially in a plane with an odd number of radially extending convolutions therein, each convolution comprising an outwardly extending portion and an inwardly returning portion of the wire, and a second winding mechanically supported by the first winding, electrically insulated therefrom, and electromagnetically coupled thereto comprising a further wire wound substantially in the form of a flat helix extending alternately over and under both portions of each successive convolution.

3. In a transformer, a first winding comprising a plurality of circular turns of wire closely grouped together wound substantially in a plane and with an odd number of radially extending convolutions therein, each convolution comprising adjacent outwardly extending portions and adjacent inwardly returning portions of the wire of the plurality of turns, and a second winding mechanically supported by the first winding, electrically insulated therefrom, and electromagnetically coupled thereto comprising a further wire wound substantially in the form of a flat helix and extending alternately over and under both portions of each successive convolutions.
